(57) **CLAIM**

The ornamental design for a tray, as shown and described.

DESCRIPTION

FIG. 1 is a top front perspective view of a tray according to a first embodiment of our new design;

FIG. 2 is bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top front perspective view of a tray according to a second embodiment of our new design;

FIG. 10 is bottom rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

In the drawings, the dash-dash broken lines show portions of a tray that form no part of the claimed design. The dash-dot lines indicate an unclaimed boundary that forms no part of the claimed design.

FIGS. 9, 10, and 13-16 show a symbolic break in width. The appearance of any portion of the tray between the break lines forms no part of the claimed design.
